UNITED STATES PATENT OFFICE.

ALBERTUS TRAVIS, OF JOHNSTOWN, NEW YORK.

FLESHING MACHINE.

Application filed April 14, 1923. Serial No. 632,071.

To all whom it may concern:

Be it known that I, ALBERTUS TRAVIS, a citizen of the United States, residing at Johnstown, in the county of Fulton and State of New York, have invented a new and useful Flesching Machine, of which the following is a specification.

This invention relates to a flesching machine and is designed more especially as an improvement upon the structures disclosed in U. S. Patents No. 1,239,985 and No. 1,239,748.

One of the objects of the invention is to provide corrugated and rubber rolls mounted in a new and novel manner for directing the hides to the knife cylinder.

A further object is to mount the knife cylinder adjustably so that it can be minutely shifted toward or from the hide being treated.

A still further object is to provide yielding means for actuating the said rolls relative to the knife cylinder so as to adapt them to hides of different thicknesses.

With the foregoing and other objects in view which will appear as the description proceeds, the invention consists of certain novel details of construction and combination of parts which will be hereinafter more fully described and pointed out in the claim, it being understood that various changes may be made in the construction and arrangement of the parts without departing from the spirit of the invention as claimed.

In the accompanying drawings the preferred form of the invention has been shown.

In said drawings:

Figure 1 is a plan view.
Figure 2 is a front elevation.

Figure 3 is a side elevation.

Figure 4 is an elevation with the drive mechanism removed, the feed roll being shown in active position relative to the flesching or knife cylinder, the parts of the machine being removed on the line 4—4 Figure 1.

Figure 5 is a section on line 5—5 Figure 1.

Figure 6 is a section on line 6—6 Figure 4.

Figure 7 is a section on line 7—7 Figure 6.

Figure 8 is a section on line 8—8 Figure 1.

Figure 9 is a section on line 9—9 Figure 8.

Referring to the figures by characters of reference 1 designates the side frames or standards of the supporting structure, these being pivotally connected as by means of a rod 2 and a rear beam 3. Each frame has an upwardly extending portion 4 near the front thereof formed with a slot 5 and in the top of this portion 4 is provided a bearing 6 in which is journaled the shaft 7 of a corrugated main feed roll 8.

Studs 9 are extended laterally from the standards 1 and mounted to swing thereon are arms 10 each of which has a pair of 70 bearings 11 and 12 at its upper end. Journaled in the bearing 11 is the shaft 13 of a rubber pressure roll 14 while the shaft 15 of a supplemental corrugated feed roll 16 is journaled in the bearings 12. See Figure 1. The shafts 13 and 15 extend through and are adapted to swing within the slots 5, the rolls 14 and 16 being interposed between the extensions 4.

Shaft 7 is provided near one end with a gear 17 and a gear 18 is also provided on one end portion of shaft 13. This gear is designed to swing into and out of mesh with gear 17 when the arms 10 are swung back and forth respectively.

Another gear 19 is secured to shaft 7 near its other end and is adapted to be engaged by a gear 20 secured to one end of shaft 15. Thus when the rolls 14 and 16 are swung toward the roll 8 gear 20 will be brought into mesh with gear 19 while gear 18 will be brought into mesh with gear 17.

The shaft 21 is journaled in the rear portion of the standards 1 and secured to this shaft close to the outer side of each standard 95 is an eccentric 22 engaged by a split strap 23 from which extends an arm 24.

A longitudinal slot 25 is formed in the arm and slidably mounted in the arm is a rod 26 pivotally connected at 27 to the adjacent swing arm 10. A coiled spring 28 is mounted on each rod 26 within slot 25 and bears at one end against one wall of the slot and at its other end against a nut 29 adjustably mounted on the rod. Thus the springs 100 on the two rods serve to hold the arms 10 normally swung toward arms 24. This swinging movement can be limited by stop nuts 30 adjustably mounted on the rods 26 and adapted to bear against arms 24.

Extending laterally from one of the standards 1 is a guide arm 31 slidably engaged by the forked end 32 of a cross head 33. This cross head is slidable between its ends on shaft 21 and has a hub portion 34 provided with an annular groove 35 for engagement by studs 36 extending from the forked end 37 of a shifting arm 38. See Figures 8 and 9. Arm 38 is connected to a rock shaft 39 extending from the rear to the front of one of the standards 1 and provided at its front end with a foot pedal 40 yieldingly supported by a spring 41 suspended from a bracket 42. A disk 43 is carried by and rotates on the shaft 21 and has a recess 44 in one face the peripheral wall of which is formed with an annular series of teeth 45. A collar 46 rotates with shaft 21 and is seated in recess 44, this collar being provided with a dog 47 pivotally connected thereto as at 48 and normally pressed outwardly by a spring 49 carried by the collar. Tripping studs 50 are extended from the respective end portions of the cross head 33 and are adapted to project into recess 44 so as to be engaged successively by the dog during the rotation of the collar 46 and shaft 21. A large pulley 51 and a small pulley 52 are connected to and rotate with disk 43, the disk and pulleys being normally mounted for free rotation on shaft 21. Under normal conditions the dog 47 is pressed against one of the studs 50 so that disk 43 can rotate freely on the shaft 21. By depressing foot pedal 40 arm 38 will swing and cause the cross head 33 to slide on shaft 21, thereby withdrawing studs 50 from the path of dog 47. Consequently spring 49 will throw the dog into engagement with one of the teeth 45, thereby coupling disk 43 to shaft 21 so as to rotate the shaft. By immediately releasing the foot pedal the studs will return to their normal positions so that after the disk 43 completes a one-half revolution the dog 47 will come against the other stud 50 and be tripped thereby so as to move out of engagement with the tooth 45. Thus the disk 43 will be automatically uncoupled from the shaft and the rotation of the shaft will be stopped. This rotation of the shaft will be sufficient to cause the eccentrics 22 to pull rods 26 longitudinally, thereby to swing arms 10 toward shaft 7 and roll 8. The skin or hide to be fleshed is first placed over the rolls 14 and 16 and obviously this movement of the arms 10 will cause the hide to be gripped between the rolls 8 and 16 while, at the same time, gear 20 will be brought into mesh with gear 19 and gear 18 will be brought into mesh with gear 17. Should the hide be of uneven thickness one or the other of the springs 28 will be free to yield during this gripping operation. When the foot pedal is next depressed so as to again release dog 47 the shaft 21 will make another one-half revolution which will be sufficient

to swing the arms 10 back to the position shown in Figure 3.

Each of the standards 1 has a bearing 53 slidably mounted thereon and journaled in these bearings is the shaft 54 of a fleshing cylinder 55 on which are provided knives 56 preferably curved as illustrated for example in Figure 1. Arms 57 are extended upwardly from the standards 1 and journaled therein is an adjusting screw 58 parallel with shaft 54 and having oppositely threaded portions 59 and 60 engaging oppositely pitched wedging blocks 61. These blocks are slidable transversely of the standards 1 in front of the respective bearings 53. It will be obvious, therefore, that by rotating screw 58 in one direction the wedges 61 will be drawn toward each other, thus to force the bearings 53 toward slots 5. By rotating the screw in the opposite direction the wedges will be moved apart and the shaft 54 is thus free to slide or shift backwardly away from the slots 5. Each of the standards is preferably formed with an upwardly abutment 62 for one of the wedge blocks 61. A hand wheel 63 or the like can be secured to one end of the screw to facilitate the rotation thereof.

Shaft 54 constitutes the drive shaft of the machine and has a pulley 64 at one end for engagement by a drive pulley. A pulley 65 is carried by the other end of the shaft and is adapted to transmit motion through a belt 66 to a pulley 67 mounted for rotation on a stud 68 projecting laterally from one of the standards 1. A gear 69 rotates with pulley 67 and meshes with a gear 70 carried by a stud 71 projecting from said standard 1. A pulley 72 rotates with gear 70 and is adapted to transmit motion through a belt 73 to the pulley 51. Another belt 74 is used for transmitting motion from the pulley 52 to a pulley 75 secured to the shaft 7.

In using the machine shaft 54 is rotating constantly and, consequently, motion is being transmitted constantly through the belts and pulleys and through the gears 69 and 70 to the shaft 7 and pulley 51 as well as disk 43.

The operator places the hide or skin on the rolls 14 and 16. Foot pedal 40 is depressed momentarily so as to cause the arms 10 to swing rearwardly and grip the hide between the rolls 16 and 8. At the same time the gears 20 and 18 will be brought into mesh with the gears 19 and 17 respectively so that while roll 8 is rotating in a clockwise direction when viewed as in Figure 3, the other rolls 14 and 16 will be rotated in a counter-clockwise direction. The two rolls 8 and 16 will thus cooperate to feed the hide upwardly over the rubber roll 14 where the surface of the hide will be engaged by the blades on the rapidly rotating fleshing cylinder 55. The hide will be fed slowly in an upward direction and when the entire sur-

face has been treated the foot pedal 40 can be depressed momentarily as heretofore explained so as to cause the arms 10 and the rolls carried thereby to swing forwardly to their initial positions. By means of the adjustment provided for the bearings 53 and illustrated in Figures 6 and 7, the fleshing cylinder can be shifted minutely toward the hide so as properly to engage the same.

10 What is claimed is:

In a fleshing machine the combination with a supporting structure, a feed roll, a fleshing cylinder, and means cooperating with the feed roll for directing a hide to the fleshing cylinder, of slidable bearings sup-

porting the fleshing cylinder, and means for simultaneously shifting the bearings to adjust the fleshing cylinder relative to the feed roll, said means including opposed wedge blocks engaging the respective bearings and an adjusting screw having oppositely fixed threads engaging the respective blocks.

In testimony that I claim the foregoing as my own, I have hereto affixed my signature in the presence of two witnesses.

ALBERTUS TRAVIS.
